UNITED STATES PATENT OFFICE.

WILLIAM A. KILMER, OF DE KALB, AND ALBERT T. WEAVER, OF JOLIET, ILLINOIS,
ASSIGNORS TO THE AMERICAN STEEL & WIRE COMPANY OF NEW JERSEY, OF
HOBOKEN, NEW JERSEY, A CORPORATION OF NEW JERSEY.

METHOD OF AND APPARATUS FOR PREVENTING FORMATION OF BURS ON ELECTRIC WELDS.

1,087,384.

Specification of Letters Patent. Patented Feb. 17, 1914.

Application filed August 23, 1912. Serial No. 716,622.

To all whom it may concern:

Be it known that we, WILLIAM A. KILMER and ALBERT T. WEAVER, citizens of the United States, residing, respectively, at De Kalb, in the county of Dekalb, State of Illinois, and Joliet, in the county of Will and State of Illinois, have invented certain new and useful Improvements in Methods of and Apparatus for Preventing Formation of Burs on Electric Welds, of which the following is a specification.

Our invention relates to the art of electric welding and has particular reference to a novel automatic device for preventing the formation of burs at the point of welding.

The practice of joining metallic articles by electric welding is well established. In such practice it is common to clamp the two parts to be welded, then pass an electric current through the contacting ends, causing the metal to be fused. At the same time one of the clamping jaws is advanced toward the other thus upsetting and causing an intimate union of the metal at the contacting ends of the article; in effect the two ends are caused to flow or fuse and to be joined as one. However, an amount of metal equal in extent to the movement of the parts toward each other is displaced and flows outside of the original contour of the article, thus forming what is usually called a bur; that is, a surplus of metal of irregular shape, which metal must be removed by turning or grinding if the article is to have a regular surface.

In the illustrations we have shown the device and described the method as applied to the wire working industry. In many cases two ends of wire are united and the resultant bur must be removed by some means before the article can be further treated or used. This entails a large amount of labor and has heretofore precluded the employment of an electric welding device in connection with wires to be passed through the galvanizing process or for nail or fabric machines.

We have devised a method and apparatus whereby the formation of the bur is prevented; that is, as the weld is being made a series of brushes are brought into contact with the wire and rapidly revolved, thus wiping off, while fluid, any surplus of metal

which would otherwise form into a bur. Thus the wire comes from the welding machine true to gage and requires no further operations in order to enable its being passed through any wire working machine.

We are aware that machines have been devised for removing the bur from welded articles, both while heated and while cold, but believe it is new to prevent the formation of a bur during the welding operation by wiping the surplus of metal from the article.

Our method may be carried out by various forms of mechanism, those shown in the accompanying drawings being preferable.

In the drawings, Figure 1 is a sectional elevation of a form of machine arranged to act in conjunction with an electric welding device; Fig. 2 is a plan view of the same machine; Fig. 3 is a section on the line 3—3 of Fig. 2, showing one welding clamp, other parts of the machine being eliminated for the sake of clearness; Fig. 4 is a fragmentary section on the line 4—4 of Fig. 2, showing a clutch operating device; Fig. 5 is an enlarged fragmentary section on the line 5—5 of Fig. 4; Fig. 6 is a fragmentary view of a part of the construction shown in Fig. 5, the engaging pin being advanced into locking position; Fig. 7 is a view on the line 7—7 of Fig. 5; Fig. 8 is an enlarged detail elevation of the brush holding and operating device; Fig. 9 is a sectional detail on the line 9—9 of Fig. 8; Fig. 10 is a side elevation of a modified construction in which the brushes are advanced mechanically as distinguished from the other form in which they are advanced by centrifugal force; Fig. 11 is an enlarged detail partly in section, showing the brush advancing means of Fig. 10; Fig. 12 is a section on the line 12—12 of Fig. 11, the parts being considerably enlarged; Fig. 13 is a section on the line 13—13 of Fig. 12; Fig. 14 is an enlarged detail view on the line 14—14 of Fig. 2, showing the electric switch operating device, and, Fig. 15 is a similar enlarged detail view on the line 15—15 of Fig. 2.

Referring more particularly to the drawings it will be seen that we provide a base or support 20, having brackets 21, 22, projecting upwardly therefrom. These brackets contain bearings within which are mount-

ed a drive shaft 23, having a drive pulley 24, mounted on one end thereof. A pinion 25 on the opposite end of shaft 23, meshes with a gear 26 mounted on a counter-shaft 27. A similar pinion 28, on the end of the shaft 27, meshes with a gear 29, keyed to shaft 30, extending from side to side of the machine. This shaft 30 carries the cams or timing devices which will be later described. A large sprocket 31, adapted to be intermittently connected with drive shaft 23, by means of a clutch later to be described, carries a sprocket chain 32, meshing with a small sprocket 33, keyed to shaft 34, which is mounted in suitable bearings 35, projected upwardly from the frame of the machine. The shaft 34 carries on one end a large gear 36, which meshes with a toothed member 37, and causes the rotation thereof. This member carries the wipers or brushes, the specific construction of which will be later described.

A welding device is associated with the machine and is composed of two sets of clamping jaws 38, 39 and 40, 41. These jaws are superposed on a base 42, and have a dove-tailed connection 43 therewith. The jaws 38, 39 are movable in the dove-tailed slot by means of the adjusting bolt 44, but are rigidly held in service. The jaws 40, 41, on the contrary, are movable toward and from the other set of jaws during each welding operation, as is well understood. In order to cause the advancement of the jaws last referred to, a stem 45 is loosely carried in an opening in the frame work of the jaws 40, 41. A stop 46 is secured to the stem 45. A compression spring 47 is located on the stem between the frame of the jaws and the stop 46, and tends to separate the stem and frame. A rigid but adjustable stop 48 is threaded into the frame of the jaws and coöperates with a projection 46^a on the stop 46. The connection between the stem of the jaw 48 and the projection 46^a is sliding. Thus it will be seen that the advancing of the jaws is not positive; that is, it is through the spring 47, but that the jaws are retracted positively through the agency of the stop 48. It will be understood that this is essential in a welding device for the reason that prior to the fusing of the joined ends of the material the metal could not easily be upset. By this construction the stem may be advanced, compressing the spring without advancing the jaws. Then when the electric current has been applied and the ends of the material are fused, the spring will advance the jaws as required. The extent of motion, which is an important element, is controlled by means which we will now describe.

For actuating the stem and jaws we provide a rocker 49, pivoted at 50 to a portion 65 of the frame. A yoke 51 on the end of the

rocker cooperates with a collar 52, secured to the stem 45, and is provided with means for adjustment longitudinally of the stem such as the hand-nut 53. A coiled spring 54 tends to hold the rocker in retracted position. The opposite end of the rocker is provided with an anti-friction roll 55, co-operating with a cam member 56, keyed to time shaft 30.

It will be understood that the welding device described in connection herewith utilizes electricity as a heating arrangement. The current, of course, cannot be constantly supplied for various reasons and in fact, the space of time within which the current is allowed to pass through the contiguous ends of the wire or of the material must be nicely controlled in order that a wire may not be burned by too great heat or not made hot enough by too short an application of the current. Therefore we have devised automatic means for momentarily closing a switch and to thereafter open the switch to shut off the current. This switch operating means is shown in Fig. 2, and in detail in Figs. 14 and 15. The switch is composed of a base member 57, insulated from the frame or base 20 of the machine. A perforated lug 58, provides a bearing for a rocker arm 59. This arm has a downwardly projecting hook 60. At its free end the arm is provided with a spring controlled contact piece 61, to which a conductor 62 is attached. The arm is held normally in elevated position by means of a spring 63. In order to avoid unnecessary arcing the switch is in the nature of a snap device; that is, the connection is made by the action of a cam 64, carried on the shaft 30, and as the hook portion 60 descends it is caught by a mating hook 65, pinned to a longitudinally movable shaft 66, and held in advanced position by means of a coiled compression spring 67. As the arm is depressed by the cam 64, the hook 60 springs past the hook 65, holding the switch in closed position. A cam 68 also mounted on the shaft 30, coöperates with a spring lever 69, held on an extension 70; this spring arm is directly connected to a lever 71, pivoted at 72 (see Fig. 2) and contacts the end of shaft 66. As the cam 68 contacts the shaft 66, it will be seen that the lever 71 is rocked and shaft 66, carrying the hook 65, moved against the resistance of spring 67, thus releasing the arm 59 and breaking the contact. Although the connections are not shown on the drawings, it will be understood that the conductors 62 and 72 are suitably connected to the welding machine terminals. An important feature is in the construction of the cam 68. As shown in Fig. 14, this cam is composed of two parts, a plain flanged member 73, having bolt holes and a slotted member carrying the cam 68; the bolts 74 project

through the slots and provide for the adjustment of the cam member relative to the shaft 30. This is arranged whereby the period of time in which the current is allowed to pass to the welding machine may be varied as required.

The bur preventing device heretofore referred to comprises the toothed member 37, and the series of brushes 75. The brushes, as shown in Figs. 8 and 9, are mounted in ways 76, in the web of the toothed member 37, the brushes having lugs or pins 77 projecting therefrom. Weighted levers 78 are pivoted to the member 37 and have slotted ends which coöperate with the lugs 77 on the brushes. When the parts are at rest the brushes are held away from the wire which is marked A in Fig. 8, by reason of a coiled spring 79. However, as the member 37 is rotated rapidly, centrifugal force will be exerted to move the weighted levers 78 and thereby advance the brushes. These brushes may be composed of any suitable material such as carborundum, or if preferred steel may be used. Provision is made for the wearing away of the brushes by mounting the pivot bolts 80 of the levers in the slots 81, in the web of the member 37. In this way as the brushes wear the levers may be moved inwardly if desired. The member 37, as shown, is provided with a concentric opening having a slot 82 communicating therewith. For this reason the member cannot be mounted to rotate on a shaft and therefore is mounted in a casing or housing 83, formed of two parts bolted together. The bearing portions of the member 37 are the flanges or ribs 84, projecting from the sides thereof and coöoperating with grooves 85 in the casing 83.

During the operation of the device the driving shaft 23 and the timing shaft 30 are constantly rotated. However, it will be understood that the brushes and the member 37 can be only intermittently rotated inasmuch as the wire to be treated must be inserted and removed through the slot 82 in the gear. Therefore we have provided an automatic clutch, as best shown in Figs. 4, 5 and 6. In these views it will be seen that a flanged member 85, is keyed to shaft 23 and rotates therewith. This member 85 is provided with a plurality of recesses 86, as best shown in Fig. 7, adapted to receive a sliding spring-pressed bolt 87, carried by sprocket-wheel 31. This bolt has an angular depending portion 88, adapted to be contacted by the wedge end 89 of a shaft 90. This shaft is normally held in lowered position by means of a coiled spring 91. The shaft has pinned thereto stops 92, with which a yoke 93, formed at one end of lever 94, pivoted at 95, coöperates. This lever has an anti-friction roll 96, at one end thereof, which roll coöperates with a cam

97, keyed to the time shaft 30. It will be seen that for each revolution of the time shaft the clutch is engaged and disengaged. Thus for a half revolution of the cam 97, the clutch is in engagement, the sprocket 70 wheel 30 is rotated, imparting motion to the brush-carrying member 37. As the cam reaches the point shown in Fig. 4, the pin will be withdrawn from the clutch member and the sprocket disengaged. 75

It will be understood that it is necessary, both in the interest of economy of time and in order to assure the registering of the slot 82 in the member 37 with the opening in the casing 83, that the parts be stopped instantly after disengagement with the constantly moving shaft. We have therefore provided brake bands 98, 98^a, the former acting on a drum keyed to shaft 34, and the latter acting on a drum formed as a part of the sprocket 31. These brake bands are both controlled by a cam 99, secured to the shaft 30. This cam coöperates with a suitable lever 100, which is rocked to tighten the band 98. A link 101, connects the lever 100 with a shaft 102, which shaft operates a lever 103, which tightens the brake band 98^a.

The mechanism for opening and closing the clamping jaws 38 to 41 inclusive, is of well known construction, being best shown 95 in Fig. 3. A cam 104, keyed to shaft 30, actuates a slide 105, connected to toggles 106. The advancing and retracting of the slide 105 rocks the clamping lever 38 about its pivot 107 as a center. The clamp may 100 be bodily adjusted by means of an adjusting bolt 108.

In the construction of Figs. 10 to 13 inclusive, we have shown a modified means for mechanically advancing the brushes 105 mounted on the toothed member. In these figures the parts, with the exception of the rotatable member, remain the same as in the former description. However, the casing 109 for the toothed member is provided with a peripheral groove 109^a, accommodating a ring 109^b. This ring 109^b is provided with segmental recesses 110, adapted to accommodate segments 111, which are cut out at intervals from a ring 112, but are adapted to be moved radially in the ways 113 therein. This ring 112 is secured to the casing 109, being held in place by bolts and clips 115. The toothed member 114 is provided with radial slots 116, within which the 110 brushes 117 are mounted, the brushes being normally retracted by means of coiled springs 118. On the outer ends of the brushes are carried rollers 119, which rollers travel, when the part 114 is in motion, 115 around the inner surface of the ring 112. The segments 111 are advanced into the position shown in Fig. 10, by shifting the ring 109^b with relation to the casing 109. This is accomplished by a face cam 120, mounted 120

125

130

on the shaft 30, and actuating the connecting rod 121, pivoted at 122 to the ring 109. When the ring is shifted the segmental portions are forced inwardly thus advancing the brushes into contact with the work.

By examining the mechanism hereinbefore described, it will be apparent that as the wire A to be acted upon is entered with its ends in contact through the slot 82, the 10 clamping jaws 38 to 41 will descend and grasp the wire. Thereupon the cam 56 will act to compress the spring 47, tending to advance the clamping jaws 40, 41, which advancement is resisted by the metal of the 15 wire. However, simultaneously an electric current is passed through the machine, due to the action of the cam which closes the switch 61, thereupon the contacting ends of the wire are fused, the jaws 40, 41 advance 20 and certain of the metal is displaced. However, during the operations just described, the clutch shown in Figs. 4 to 6 is actuated and the rotatable toothed member 37 is rapidly rotated, thus advancing the brushes into 25 contact with the wire at the point of fusion. The surplus metal is thereupon wiped from the exterior of the wire and as the cycle of operations is completed, the member 37 is stopped, the brushes are retracted, the 30 clamps released and the wire removed from the machine true to gage and properly welded. All the operations just described follow each other with such rapidity that the complete operation is performed in a 35 few seconds.

It will be obvious from the description that the parts herein referred to as brushes might be in the form of milling tools or might be constructed of abrasive material 40 and that the bur might be turned or ground off after formation. It is therefore to be understood that the word "brush" is used broadly in the claims and covers any form of tool adapted for the purpose of wiping 45 away, abrading, or turning off the excess metal at the time of or immediately following the welding operation.

We are aware that the mechanism herein described may be changed in many ways to 50 apply it to other industries; we are also aware that many of the elements herein described and shown may be changed by their mechanical equivalents. We therefore do not wish to be limited to the exact structure 55 herein shown and described.

We claim:

1. In a device of the class described, the combination of means for holding two ends of material to be joined, means for fusing the joined ends whereby a weld is formed, and rotatable means for removing the surplus metal from the material at the weld, said 60 rotatable means for removing the surplus metal being movable about a fixed center, substantially as described.
- 65 2. In a device of the class described, the

combination of means for holding two ends of material to be joined, means for fusing the joined ends whereby a weld is formed, and rotatable means for removing the surplus metal from the material at the weld, said 70 rotatable means acting while the material is still plastic, substantially as described.

3. In a device of the class described, the combination of means for holding two ends of material to be joined, means for fusing the joined ends whereby a weld is formed, and means for removing the surplus metal from the material at the weld, said removing 75 means being movable about a fixed center, substantially as described.

4. In a device of the class described, the combination of means for clamping the material to be acted upon, means for fusing the contacting ends of the material and causing an intimate union thereof, a brush mounted for rotation around said material as an axis, whereby surplus metal is wiped from the material while such metal is plastic, substantially as described.

5. In a device of the class described, the combination of means for clamping the material to be acted upon, means for fusing the contacting ends of the material and causing an intimate union thereof, and a series of brushes mounted for rotation around said material as an axis, whereby surplus metal is wiped from the material while such metal is plastic, substantially as described.

6. In a device of the class described, the combination of a pair of clamps for holding the ends of material to be united, means for simultaneously passing an electric current through said material and advancing one of said clamps whereby the metal is upset, a rotatable member surrounding said material in the plane of the joined ends, means for rotating said member, and a tool carried by said rotatable member and adapted to remove the upset metal, substantially as described.

7. In a device of the class described, the combination of a welding device having two sets of clamping jaws, a rotatable member mounted between said sets of jaws, and brushes carried by said rotatable member, 115 said brushes being adapted to wipe surplus metal from the material during the welding operation, substantially as described.

8. In a device of the class described, the combination of a welding device having two sets of clamping jaws, means for operating 120 said jaws to clamp a wire therebetween, means for advancing one set of jaws and simultaneously passing an electric current through said wire whereby the wire is fused at the contacting ends, a slotted, rotatable member mounted between the two sets of clamping members, the axis of said rotatable member being coincident with said wire, brushes carried by said rotatable member, 125 130

and means for automatically advancing said brushes into contact with the wire during the rotation of said member and withdrawing the brushes out of contact with the wire 5 when the rotation of said member is stopped, substantially as described.

9. In a machine of the class described, the combination of a constantly driven element and an intermittently driven element, a series of timing devices driven by said constantly moving element, a rotatable brush-carrying member actuated by said intermittently driven element, a brush on said rotatable member, said brush being adapted 15 to contact the surface of material and remove irregularities therefrom, and means for connecting and disconnecting said constantly and intermittently moving elements whereby definite cycles of operation are assured, substantially as described.

10. In a machine of the class described, the combination of a drive shaft, a counter-shaft, timing devices carried by said counter-shaft, two sets of clamping jaws, means operable by a timing device on said counter-shaft adapted to cause the advancing of one of said sets of jaws, a rotatable member mounted between said sets of jaws, means for causing intermittent rotation of said rotatable member, and brushes carried by said rotatable member, said brushes being adapted to contact material held by said clamping jaws, substantially as described.

11. In a device of the class described, the combination of a drive shaft, a driven shaft, timing devices on said driven shaft, electric welding clamps one set of which is movable transversely under the action of a timing device on said driven shaft, a rotatable member mounted between said sets of clamping jaws, brushes carried by said rotatable member and means operable from said drive shaft for rotating said rotatable member, substantially as described.

45 12. In a device of the class described, the combination of a welding device having two sets of relatively movable clamping jaws, brushes adapted to be rotated about an axis coincident with the material to be welded, and automatic means for bringing said brushes into contact with the work during

rotation and withdrawing the same therefrom when the brushes are idle, substantially as described.

13. In a device of the class described, the combination of a welding device having relatively movable clamping jaws, a series of brushes mounted between said sets of clamping jaws and adapted to be rotated about an axis coincident with the material to be welded, and means operable by centrifugal force for bringing said brushes into contact with the work, substantially as described.

14. In a device of the class described, the combination of a welding device having relatively movable clamping jaws, a series of brushes mounted between said sets of clamping jaws and adapted to be rotated about an axis coincident with the material to be welded, and means operable by centrifugal force for bringing said brushes into contact with the work against an opposed force, which opposed force tends to remove the brushes from contact with the work when rotation has ceased, substantially as described.

15. The method of preventing the formation of burs in welding, which consists in holding the ends of material to be joined, then fusing said ends to form an intimate union thereof, then wiping the surplus metal from the material at the point of weld while the metal is still plastic, substantially as described.

16. The method of preventing the formation of burs in welding, which consists in holding the ends of material to be joined, then fusing said ends to form an intimate union thereof, and simultaneously wiping away any excess of metal, thereby retaining the original contour of the material, substantially as described.
